AMPLIFICATION SYSTEM

Application filed October 10, 1925. Serial No. 61,687.

This invention relates to amplifier systems, and, more particularly, to systems for the amplification of radio-frequency signals.

In the past, multistage radio-frequency amplification systems have been designed using coupling transformers of identical design in each stage of amplification. Measurements and mathematical analyses indicate that the amplification in such systems is greatest in the shortest wave length, or highest frequency, and is only a fractional part of this value in the longest wave length, or lowest frequency. As each stage has its maximum amplification at the same frequency, the addition of successive stages will accentuate this point of amplification in geometric ratio, with the result that when three or more stages are employed the aggregate amplification is extremely high at one frequency and comparatively low at all others. Obviously this feature is not desirable.

The present invention has for its object the provision of appropriate coupling means between the individual stages of a multistage tuned radio-frequency amplifier so that any desired ratio of maximum to minimum amplification may be obtained within the limits of the device.

It has been recognized that in a multistage tuned radio-frequency amplifier designed to operate over a wide wave length or frequency band, the amplification varies with the frequency of tuning in a manner dependent upon the specific construction of the coupling transformers. In former multistage tuned amplifiers employing fixed values of inductance for both primary and secondary windings of the interstage transformers, with variable condensers as a means of tuning, the construction of the transformers has been such that the voltage developed across the terminals of the secondary winding, and hence the amplification and relay action is a maximum when the smallest value of tuning condenser is used. This effect is due to the fact that when a capacity is shunted across the terminals of the secondary winding of an interstage transformer, and is varied so as to enable the receiver in which it is incorporated to respond over a wide wave-length or fre-

quency range, the reactance of the secondary winding, and proportionately the voltage developed across it, will vary, both being a maximum when the smallest value of capacity is used, and a minimum when the largest value of capacity is used.

The primary winding of the transformer which is included in the output circuit of the preceding vacuum tube, is closely coupled to the secondary winding thereof, and depends largely for the value of its impedance upon the impedance of the circuit in which the secondary winding is connected, with the result that when the impedance of the secondary circuit varies with changes in the tuning capacity, the effective impedance of the primary circuit coupled thereto also varies. This invention takes advantage of the well-known principle that the maximum output of a vacuum tube is obtained when the external or load impedance is substantially equal to the internal impedance of the tube. It follows that each stage of the radio-frequency amplifier, including its vacuum tube and transformer, will manifest a maximum relay action at that one frequency or wave-length which obtains when the internal and output circuit impedances are matched. For practical purposes a tuning range for each stage measured a certain distance each side of the actual peak or point of maximum amplification frequency, will give satisfactory quantitative amplification. This frequency band we may call the mean maximum amplification-frequency band. The present invention provides an arrangement of interstage transformers, each with its vacuum tube, having a different mean maximum-frequency band, the ranges of these bands progressing successively so that the envelope of the aggregate of the bands will indicate substantially constant amplification over the desired frequency range of the receiver.

For a more complete understanding of the invention reference is made to the drawings, together with the following description of a preferred embodiment, in which

Fig. 1 discloses a radio receiver comprising a three-stage radio-frequency amplification system and a detector;

Fig. 2 is a chart having curves showing the amplification effected by former radio-frequency amplifiers as compared with the radio-frequency amplifier of the present invention;

5 Fig. 3 shows a second chart indicating the amplification effected by the several stages of the radio-frequency amplifier, which in the aggregate produce a substantially straight line amplification, as indicated in the chart 10 of Fig. 2; this figure also shows that with various coupling transformers the relay action varies for different wave lengths or frequencies, and that it is impossible to obtain 15 strictly the maximum relay action for all frequencies within the desired band without a change in coupling between the several stages.

In Fig. 1 there is disclosed the circuit diagram of a three-stage radio-frequency amplifier and detector combined in a radio receiving set, and provided with an antenna directly coupled to the tuned circuit including the inductance T_1 and variable capacity C_1 of 20 the first stage of the amplifier, indicated by vacuum tube V_1 . The output circuit of this tube is coupled to the tuned input circuit of a second stage of amplification, including 25 vacuum tube V_2 , by means of a radio-frequency transformer T_2 . In accordance with practice now well known, a neutralizing condenser C_{n1} connects the grid circuit of vacuum tube V_1 to an appropriate point on the secondary winding of transformer T_2 to neutralize the undesirable capacity coupling of 30 tube V_1 and thereby to prevent all capacity reaction between the input circuit and the output circuit of this vacuum tube. The output circuit of vacuum tube V_2 , in the second 35 stage of the amplifier, is coupled by means of a radio-frequency transformer T_3 to the tuned input circuit of vacuum tube V_3 , of the third radio-frequency stage. As in the case of the first radio-frequency stage, a neutralizing condenser C_{n2} connected to the grid 40 circuit of vacuum tube V_2 , and to an appropriate point on the secondary coil of transformer T_3 , likewise neutralizes any capacity reaction effects between the input circuit 45 and the output circuit of the vacuum tube V_2 . In like manner, the output circuit of vacuum tube V_3 , of the third stage of amplification, is coupled by means of a radio-frequency transformer T_4 to the input circuit of the 50 detector, the vacuum tube of which is designated V_4 . A neutralizing condenser C_{n3} neutralizes capacity reaction effects between 55 the input and output circuits of the third radio stage.

60 In accordance with the present invention, the radio-frequency transformers T_2 , T_3 and T_4 are so selected that in the aggregate they effect substantially straight line radio-frequency amplification, as indicated in Fig. 2, 65 in which the curve designated "2" indicates

the resultant amplification of the receiver of Fig. 1 and shows the improvement in amplification at the lower frequencies, as compared with present commercial radio-frequency amplifiers, the latter being illustrated by the 70

curve designated "1", in Fig. 2. To effect this improved amplification, transformer T_2 coupling the first and second stages of the amplifier is selected so that it effects mean maximum amplification at a low wave length, as indicated by curve A, Fig. 3. To illustrate, if the internal impedance of tube V_1 is 10,000 ohms under given conditions, the maximum relay action will be obtained when the output circuit is also of 10,000 ohms impedance. The primary winding of transformer T_2 is therefore so designed and coupled to the secondary winding that when condenser C_2 is tuned to about 267 meters the input circuit of the transformer at resonance will have an effective impedance of 10,000 ohms. Likewise, transformer T_3 , coupling the second and third vacuum tubes, V_2 and V_3 , is designed to effect mean maximum amplification at an intermediate wave-length, as indicated by curve B, 80 Fig. 3, by designing the input circuit of the transformer to have an effective impedance of 10,000 ohms when the secondary circuit is tuned to 400 meters. Likewise, transformer T_4 , coupling the output circuit of vacuum tube V_3 to detector V_4 , is designed to effect its 85 mean maximum amplification at a high wave-length, as indicated by curve C, because the input circuit at resonance will be of 10,000 ohms effective impedance when the secondary circuit is tuned to about 533 meters. The aggregate and resultant amplification of the 90 three transformers and their associated vacuum tube circuits, is shown by the curve designated "2", in Fig. 2, which indicates nearly 95 straight-line amplification from 200 to 600 meters the entire range of the receiver. Transformers T_2 , T_3 and T_4 , as well as coil 100 T_1 , are preferably arranged in such a manner 105 as to eliminate undesirable electromagnetic coupling between them, whereby improved 110 amplification will be realized.

The invention may be explained from another point of view as follows. The intermediate wave-length, such, for example, as 400 meters, the first stage transformer is of 115 less effective input impedance at resonance (the frequency of tuning) than that of the output circuit of the vacuum tube to which it is connected; the effective input impedance at resonance of the second stage transformer 120 at 400 meters being equal to the output circuit impedance of the vacuum tube to which it is connected; the effective input impedance at resonance at 400 meters of the transformer in the third stage being greater than the impedance of the output circuit of its associated vacuum tube. This desired result is at 125 130

tained because there is less dielectric loss and greater amplification in the first stage on short wave-lengths when the effective input impedance at resonance of the first stage coupling transformer is less than the impedance of the output circuit of its associated vacuum tube. Likewise, on the longer wave-length, maximum amplification will be obtained in the third stage when the effective input impedance at resonance of the transformer at 10 meters is greater than the output circuit impedance of the vacuum tube in that stage. The second stage transformer would in this case be designed to have characteristics similar to the second stage transformer in the first-mentioned arrangement, namely, the effective input impedance at resonance of the transformer at 400 meters would be equal to the output circuit impedance of the vacuum tube 20 in that stage.

I claim:

1. In a multi-stage tuned radio-frequency vacuum tube amplifier, each stage being coupled to the next adjacent stage by a single 25 transformer, a variable condenser associated with each transformer in a tuned circuit for tuning the same over a predetermined wave-length range, the effective input impedance of each transformer at resonance being adjusted to such value that the ultimate amplification of all of said stages is substantially 30 constant throughout said wave-length range when all of said condensers are adjusted so that their respective tuned circuits are substantially in resonance with each other.

2. In a multi-stage tuned radio-frequency vacuum tube amplifier, each stage being coupled to the next adjacent stage by a single 40 transformer, a variable condenser associated with each transformer in a tuned circuit for tuning the same over a predetermined wave-length range, the effective input impedance of each transformer at resonance being adjusted to such value that the ultimate amplification of all of said stages is substantially 45 constant throughout said wave-length range when all of said condensers are adjusted so that their respective tuned circuits are substantially in resonance with each other, and 50 means for eliminating undesirable electro-magnetic coupling between the secondary windings of the several interstage transformers whereby improved amplification may be realized.

3. In a multi-stage tuned radio-frequency vacuum tube amplifier, each stage being coupled to the next adjacent stage by a single 55 transformer, a variable condenser associated with each transformer in a tuned circuit for tuning the same over a predetermined wave-length range, the effective input impedance of each transformer at resonance being adjusted to such value that the ultimate amplification of all of said stages is substantially 60 constant throughout said wave-length range

when all of said condensers are adjusted so that the tuned circuits in which said condensers are respectively connected are substantially in resonance with each other, means for eliminating undesirable electro-magnetic coupling between the secondary windings of the several interstage transformers, and means including a winding of an interstage transformer for neutralizing undesirable capacity coupling in at least one of 70 said stages whereby increased amplification 75 may be realized.

4. In a multi-stage tuned radio-frequency vacuum tube amplifier, each stage being coupled to the next adjacent stage by a single 80 transformer, a variable condenser associated with each transformer in a tuned circuit for tuning the same over a predetermined wave-length range, the effective input impedance at resonance of one of said transformers over 85 a certain frequency range being less than the output impedance of the tube in whose output circuit the primary winding of said transformer is connected, another of said transformers having over the same frequency 90 range an effective input impedance at resonance which is greater than the output impedance of the vacuum tube in whose output circuit the primary winding of said other transformer is connected.

5. In a multi-stage tuned radio-frequency vacuum tube amplifier, each stage being coupled to the next adjacent stage by a single 95 transformer, a variable condenser associated with each transformer in a tuned circuit for tuning the same over a predetermined wave-length range, the effective input impedance at resonance of one of said transformers over a certain frequency range being less than the output impedance of the vacuum tube in whose output circuit the primary winding of said transformer is connected, a second one of said transformers having over the same frequency range an effective input impedance at resonance which is substantially equal to 100 the output impedance of that vacuum tube in whose output circuit the primary winding of said second transformer is connected, and a third one of said transformers having over the same frequency range an effective input impedance at resonance which is greater than the output impedance of the vacuum tube in whose output circuit the primary winding of said third transformer is connected.

6. In an amplifier, a plurality of tuned 110 amplifying stages, each stage including a vacuum tube, and means for tuning said stage to a plurality of narrow frequency bands within a relatively wide frequency range, said means including a transformer 115 serving to couple the output circuit of one vacuum tube to the input circuit of a succeeding vacuum tube, the effective input impedance at resonance of one of said transformers over a certain frequency range be- 120 125 130

- ing substantially equal to the output impedance of the vacuum tube in whose output circuit said transformer is connected, a second of said transformers having over a second frequency range an effective input impedance at resonance which is substantially equal to the output impedance of the vacuum tube in whose output circuit said second transformer is connected, and a third of said transformers having over a third frequency range an effective input impedance at resonance which is substantially equal to the output impedance of the vacuum tube in whose output circuit said third transformer is connected.
- 15 7. In an amplifier, a plurality of tuned amplifying stages, each stage including a vacuum tube, and means for tuning said stage to a plurality of narrow frequency bands within a relatively wide frequency range, said means including a transformer serving to couple the output circuit of one vacuum tube to the input circuit of a succeeding vacuum tube, the effective input impedance at resonance of one of said transformers over a certain frequency range being substantially equal to the output impedance of the vacuum tube in whose output circuit said transformer is connected, a second of said transformers having over another frequency range an effective input impedance at resonance which is substantially equal to the output impedance of the vacuum tube in whose output circuit said second-mentioned transformer is connected.
- 25 8. In an amplifier, a plurality of amplifying stages, each stage including a vacuum tube, a plurality of transformers each serving to couple the output circuit of one vacuum tube to the input circuit of another vacuum tube of said amplifier, and means for tuning each transformer continuously over a predetermined frequency band, the value of the impedance of the primary circuit of each transformer being a function of the impedance of the secondary circuit thereof, the impedance of said primary circuit at a certain mean maximum amplification frequency being substantially equal to the internal impedance of the tube in that stage, the impedance of the primary circuit of another stage at a mean maximum amplification frequency different from that of said first-mentioned stage being substantially equal to the internal impedance of the vacuum tube in said other stage.
- 35 9. In a multi-stage radio-frequency vacuum tube amplifier, each stage being coupled to the next adjacent stage by a single transformer having a primary winding and a secondary winding, means including the secondary winding of each transformer for tuning the same over a predetermined wavelength range, the effective input impedance at resonance of one of said transformers over a certain frequency range being less than the

output impedance of the tube in whose output circuit the primary winding of said transformer is connected, another of said transformers having over the same frequency range an effective input impedance at resonance which is greater than the output impedance of the vacuum tube in whose output circuit the primary winding of said other transformer is connected.

10 10. In a tuned radio-frequency receiver, a plurality of vacuum tubes coupled by radio-frequency transformers in cascade relation, each transformer having a tuned circuit and means for tuning said circuit over a certain frequency range, the effective input impedance of each transformer at resonance being adjusted to such value that the resultant amplification of all of said stages is nearly constant throughout said frequency range when all of said tuned circuits are adjusted so as to be substantially in resonance with each other.

15 11. In a multi-stage tuned radio-frequency amplifier, the method of amplifying radio signals which comprises tuning said stages to resonance with the frequency of said signals, selectively amplifying said signals to a different degree in each stage at the same given frequency within a relatively wide frequency range, and amplifying said signals in any given stage of said amplifier to a different degree at different frequencies within said range, whereby the degree of amplification of said multistage amplifier is substantially uniform throughout the tuning range thereof.

20 12. The combination in a high-frequency amplifying system tunable throughout a specified frequency range, of a plurality of thermionic tubes arranged in cascade, each tube having an input section and an output section, means coupling the output section of each said tube to the input section of a succeeding tube, one said coupling means including but a single transformer, said transformer having the characteristic that it is most efficient in transferring energy at the lower frequencies of said frequency range, and a different said coupling means including but a single transformer, said transformer having the characteristic that it is most efficient in transferring energy at the higher frequencies of said frequency range.

25 13. The combination in a tuned high-frequency amplifying system effective throughout a specified frequency range, of a plurality of vacuum tubes arranged in cascade, means coupling an output circuit of each said tube to a tunable input circuit of the succeeding tube, one said coupling means including but a single transformer, said transformer having the characteristic that it is most efficient in transferring energy at the lower frequencies of said frequency range, and a different said coupling means including but a single trans-

former, said last named transformer having the characteristic that it is most efficient in transferring energy at the higher frequencies of said frequency range.

14. The combination in a tuned high-frequency amplifying system effective throughout a specified frequency range, of a plurality of vacuum tubes arranged in cascade, each having an output circuit coupled to a tunable input circuit of the succeeding tube, a single transformer connected in the output circuit of one of said tubes, said transformer having the characteristic that it is most efficient in transferring energy at the lower frequencies of said frequency range, and a single transformer connected in the output circuit of another of said tubes, said transformer having the characteristic that it is most efficient in transferring energy at the higher frequencies of said frequency range.

15. The combination in a tuned high-frequency amplifying system effective throughout a specified range of frequencies, of a plurality of thermionic tubes arranged in cascade, each having an output circuit coupled to a tunable input circuit of the succeeding tube, a single transformer connected in the output circuit of one of said tubes, said transformer having the characteristic that it is most efficient in transferring energy at the lower frequencies of said frequency range, and a single transformer connected to the output circuit of another of said tubes, said transformer having the characteristic that it is most efficient in transferring energy at the higher frequencies of said frequency range, said transformers being so related that the overall amplification of the system is substantially constant throughout said frequency range.

16. The combination in a tuned high-frequency amplifier effective throughout a specified frequency range comprising a plurality of cascaded vacuum tube stages of the type including means suppressing the effects of capacitive coupling between control grid and plate, each tube having an output circuit coupled to a tunable input circuit of the succeeding tube, of a single transformer connected in the output circuit of one said tube, said transformer having the characteristic that it is most efficient in transferring energy at the lower frequencies of said frequency range, and a single transformer connected in the output circuit of another of said tubes, said transformer having the characteristic that it is most efficient in transferring energy at the higher frequencies of said frequency range.

17. The combination in a tuned high-frequency amplifying system effective throughout a specified range of frequencies, of a plurality of vacuum tubes arranged in cascade, each having an output circuit coupled to a tunable input circuit of a succeeding tube, a first transformer connected in the output cir-

cuit of one of said tubes, and a second transformer connected in the output circuit of another of said tubes, said transformers being so arranged that the primary circuits thereof have different impedance characteristics whereby one said transformer is most efficient in transferring energy at the lower frequencies of said frequency range, and the other of said transformer is most efficient in transferring energy at the higher frequencies of said frequency range.

In testimony whereof I affix my signature.
